(57) **CLAIM**

The ornamental design for a solar collector panel, as shown and described.

DESCRIPTION

FIG. 1: is a perspective view of a solar collector panel showing my new design.

FIG. 2: is a front view thereof;

FIG. 3: is a rear view thereof.

FIG. 4 is a right end elevational view thereof;

FIG. 5 is a left end elevational view thereof;

FIG. 6 is a top plan view thereof; and,

FIG. 7 is a bottom plan view thereof.

The broken line shown in FIGS. 6 and 7 is included for the purpose of illustrating environmental structure only and forms no part of the claimed design.
